US00D722895S

(12) **United States Design Patent**
Chandran

(10) **Patent No.:** **US D722,895 S**
(45) **Date of Patent:** **** Feb. 24, 2015**

(54) **FLUID DELIVERY DEVICE**

(71) Applicants: **Robert Bosch Tool Corporation**,
Broadview, IL (US); **Robert Bosch
GmbH**, Stuttgart (DE)

(72) Inventor: **Anand Chandran**, Dunlap, IL (US)

(73) Assignee: **Robert Bosch GmbH**, Stuttgart (DE)

(**) Term: **14 Years**

(21) Appl. No.: **29/434,635**

(22) Filed: **Oct. 15, 2012**

(51) LOC (10) Cl. **10-03**

(52) U.S. Cl.

USPC **D10/40**

(57) **CLAIM**

The ornamental design for a fluid delivery device, as shown and described.

DESCRIPTION

FIG. 1 is a front perspective view of a fluid delivery device showing my new design;

FIG. 2 is a front elevational view showing the design for the fluid delivery device of FIG. 1;

FIG. 3 is a left side elevational view showing the design for the fluid delivery device of FIG. 1;

FIG. 4 is a right side elevational view showing the design for the fluid delivery device of FIG. 1;

FIG. 5 is a top plan view showing the design for the fluid delivery device of FIG. 1; and,

FIG. 6 is a bottom plan view showing the design for the fluid delivery device of FIG. 1.

The broken line showing of portions of the fluid delivery device is included for the purpose of illustrating environmental structure and forms no part of the claimed design.

1 Claim, 6 Drawing Sheets
